CAR DOOR OPERATING IMPLEMENT

Thomas H. Edelblute, Reynoldsville, Pa.

Application August 31, 1938, Serial No. 227,729

11 Claims. (Cl. 254—131)

This invention relates to a chain and jack type of pulling device especially designed and intended for use in operating the doors of railroad cars, but is also applicable to other purposes.

Considerable difficulty is frequently encountered in opening and closing the doors of box cars. Frequently the combined efforts of several men are required to operate a door and often use is made of crow-bars and other prying devices. Also, many injuries to the hands occur in the closing of the hopper doors of gondola cars or other injuries result from the efforts of workmen to close such doors. Not infrequently it is necessary for the workman to lie down on his back under a gondola car and push the hopper door shut with his feet.

The present invention provides a convenient tool or implement to be used in opening or closing the doors of box cars. It is of a character such that it can be used on all types of box cars and in various positions. For example, in some places the box car is loaded or unloaded from a platform where the floor of the freight car is on the same level as the platform so that anyone operating the door is standing on a plane level with the floor of the car. In other cases the door has to be opened by someone standing on the ground possibly in a narrow space alongside a building or warehouse or from a pathway that is considerably lower than the rails on which the car is standing. The implement provided by the present invention is applicable to use with equal convenience in these various locations. The invention provides a tool which has a removable attachment to enable the tool to be used in closing the doors of gondola cars without likelihood of injury to the fingers or hands of the workman and without necessitating that he get under the car.

The present invention, moreover, provides an implement of this character which, while specifically applicable to use in connection with car doors, can also be used for performing miscellaneous pulling operations as for example the moving of heavy objects over a station platform, and which is of a simple rugged construction that may be built to sell for a low price and which is more convenient to use than more expensive devices heretofore provided for this purpose.

The invention may be readily understood by reference to the accompanying drawings which illustrate certain preferred embodiments of my invention and in which:

Figure 1 is a more or less schematic view showing the implement being used for closing the door of a box car;

Figure 2 is a similar view showing the implement being used to open a box car door;

Figure 3 is a side elevation of the implement itself;

Figure 4 is a top plan view of the implement shown in Figure 3;

Figure 5 is a detailed view showing on a larger scale a longitudinal section through a portion of the implement;

Figure 6 is a side view partly in section of the operating end of the implement with the attachment applied thereto through which the device is used for operating the doors of gondola cars;

Figure 7 is a top plan view of the portion of the tool shown in Figure 6;

Figure 8 is a view similar to Figure 5 showing a slightly modified arrangement;

Figure 9 is a sectional view in substantially the plane of line IX—IX of Figure 8.

The implement comprises an elongated rigid handle member having a handle portion 2, a terminal portion 3, and an intermediate portion 4 having integral parallel side bars 4a with an open space therebetween. Opposite the terminal portion 3 is an end 5 which is preferably of a wedge shape to enable the tool to be used as a pry or a crow bar. The end portion 3 of the handle member is bifurcated, and passing through the bifurcated end is a pin 6. This pin supports a member 7, which member has a projecting portion 8 with a bore 9 therethrough, the bore being at right angles to the pin 6. Passing through the bore 9 is the shank 10 of a hook 11. A nut 10a on the other end of the shank 10 serves to hold the hook member in place. By reason of the hook 11 being pivoted to rotate about the axis of the shank 10 and also being carried in the member 7 which is pivotally supported on the pin 6, the hook has a universal mounting at the end of the handle. The member 7 is preferably provided with projecting lugs 1a and 1b on its inner end. An integral transverse stop 12 extends across the bifurcated portion of the handle so as to be in the path of travel of the lugs 1a and 1b so that the pivoting movement of the hook about the pin 6 is limited in one direction by the contact of lug 1b with the cross member 12 and in the other direction by the contact of the lug 1a with the member 12. It is desirable to limit the range of pivoting movement in this direction, as hereinafter described.

Back of the bifurcated end portion and back of the stop 12 there is preferably a cross web 13 to strengthen the construction and which also preferably has holes 14 therein for the purpose hereinafter described. Between the cross web 13 and the beginning of the solid portion of the handle 2 there is an opening 15 through the intermediate portion of the handle between the side members 4a. A chain engaging pawl or dog 16 is positioned in the opening 15, this pawl being pivotally supported on a cross pin 17. The pawl has a chain engaging terminal portion 16a and an oppositely extending arm portion 16b. The implement is formed with a cross piece 18 between the two side bars 4a which cross piece is parallel with the pivot pin 17 for the pawl and which has inclined surfaces on the inner face thereof, one of which forms a stop to engage and limit the rocking movement of the pawl in a clockwise direction as viewed in Figure 5 and the other inclined face of which connects the arm 16b of the pawl to limit the rocking movement of the pawl in a counterclockwise direction as viewed in this figure. A cross piece 19 extending between the side portions 4a is provided with a socket 20 in which is one end of a compression spring 21, the other end of this spring being seated in a recess in the arm 16b of the pawl. The spring thus normally urges the arm 16b toward the abutment member 18 which is the position of the parts illustrated in Figure 5 and the abutment prevents the pawl from rotating to a point where the spring would fall out. Adjacent the chain engaging terminal 16a of the pawl or dog 16 is cross piece 22. This is preferably a separate member formed of square steel stock and passing through square openings in the side members 4a and retained in place by cotter pins at each end thereof. This cross piece forms a chain stop to cooperate with the pawl.

Passing between the chain stop 22 and the terminal 16a of the pawl is a link chain 23. This chain may be of any desired length and it is preferably provided with a hook 24 at one end as shown, for example, in Figures 1 and 2. The chain may be readily pulled through the opening 15 in the direction of the arrow in Figure 3. When it is pulled in this direction, the successive chain links riding over the stop 22 move the pawl 16 in a clockwise direction enabling the chain to easily pull through the device. When the lever is pulled in the direction of the arrow in Figure 3, one link is flat and firmly pressed by the pawl top 16a against the stop 22. The succeeding link to the flat one hits against the chain stop. It tends to slide up the chain stop, but this movement is resisted by the thrust endwise against the pawl, the line of thrust being on a line of dead center so that the pawl does not rotate. When it is desired to release the pawl to enable the chain to be pulled through to a direction opposite the direction of the arrow in Figure 3, pressure has to be applied manually to the arm 16b of the pawl. A swivel 23a in the chain is desirable, as it avoids twists which interfere with the operation of the device when the chain becomes short, i. e., when the operating device approaches close to the hook end of the chain.

In using the device as illustrated in Figures 1 to 5 inclusive, the hook 11 on the implement is hooked into the handle of a box car door. In some cases these handles are horizontal and in other cases they are vertical. The hook 11 can

be hooked into either horizontal or vertical handles with equal facility. If the implement is to be used in closing a car door as shown in Figure 1, the hook 24 on the end of the chain is anchored to some part of the car toward which the door is to be moved. In Figure 1 this hook is illustrated as being engaged in a hasp that is commonly provided alongside the door frame of a box car. In some instances it would be hooked to some part of the under rigging of the car. It is only important that the hook 24 be anchored at that end of the car toward which the door is to be moved. The operator then grasps the free end of the chain in one hand and with the other he rocks the lever about its pivot 6 in a direction away from him. In this movement of the lever away from him the pawl 16 will ride over the chain links. The lever may be thrust forward any convenient distance until the abutment 12 engages the lug 1a which limits the maximum forward swing of the lever. He then pulls the lever back toward him using either one or both hands. The chain will be held against relative movement between the pawl and the chain stop 22 so that the lever cannot slip back over the chain, and causes the car door to be pulled in the direction of the arrow in Figure 1. By reason of the relatively great leverage that can be exerted in this way, the door may be moved with ease. The lever may be pulled toward the operator until the 30 abutment 12 hits the lug 1a of the member 1 which limits the backward pull of the lever. This operation is repeated until the door is closed. By reason of the universal connection between the hook and the lever, the lever may be swung 35 to any suitable angle, and it can be used by one walking below the car and close to the side of it or by one walking along a platform which is level with or above the car floor. Moreover, the hook will accommodate itself to doors having 40 either vertical or horizontal handles.

In opening a car door, the same operation is followed, the hook 24 being anchored to some point on the car frame forwardly in the direction to which the door is to be moved. This is 45 illustrated in Figure 2. The lever is manipulated in the same way for either opening or closing the door. The advantage of limiting the arc through which the lever may be swung with reference to the hook carrying member 1 may be readily understood. If, for example in Figure 2, the lever could be swung to a position where it was nearly horizontal, the chain would lie at only a slight angle with respect to the stop member 22, and the pawl 16 would be less effective for holding 55 the chain and the leverage exerted in pulling the handle back would be less effective than it is where the handle or lever is at a greater angle to the chain. Also, when the handle is swung forward away from the operator and strikes lug 60 1b, it tends to rotate member 1 in which the hook 11 is carried, forcing the hook into a better holding position with the door handle. If the lever could be pulled back too far toward the operator, the relation of the chain with respect 65 to the locking pawl and the stop would be such that the chain might slip.

When it is desired to use the tool for closing the hopper doors of gondola cars, the pin 6 is removed to permit removal of the member 1 with the hook 11. In place of this member a terminal member of the shape shown in Figures 6 and 7 is substituted. This terminal member which is made of rigid metal has an inner end portion 25 adapted to be received in the bifur- 75

cated end of the lever 2, this end portion 25 having an opening through which the pin 6 may pass. It is provided also with two spaced-apart inwardly extending projections 26, these projections being adapted to enter the holes 14 in the cross member 13. The stop member 12 is received in the space between the two projections. This arrangement provides a way of forming a rigid extension for the lever 2 using the same pin 6 as used for holding the member 7 on the lever. Only the single pin has to be removed to replace one member with the other. This attachment preferably has an offset 27 therein beyond which is an extension 28 preferably terminating in a wide 15 wedge shaped terminal 29.

In using this device, the chain is pulled through the dog until there is only a short length of chain between the dog and the hook 24. The swivel 23a is located at a proper distance to provide a 20 convenient measure of the short length of chain necessary. The hook 24 is secured to the hopper door. The terminal part 29 of the implement is placed back of the inclined bottom of the hopper. The lever 2 is then moved in a direction to close 25 the door. In this operation the door is pulled shut with a single movement of the lever and there is no relative motion between the chain and the lever. In Figure 6 the hook 24 is not shown but will be on the lower end of the chain as this 30 figure is viewed from the bottom of the sheet. The offset 27 enables the tool to more conveniently engage the inclined bottom of the hopper than if the attachment were straight.

Instead of providing for a universal movement 35 of the hook 11 through the use of the transverse pins 6 and 10, the modification shown in Figures 8 and 9 may be employed where the connection between the hook and the lever is a ball and socket type of connection. The arrangement 40 shown in Figures 8 and 9 is illustrated merely to show another type of universal mounting for the hook and is slightly more expensive than the preferred embodiment. In this figure 30 designates the lever having an opening 31 through one 45 end thereof to receive the chain engaging dog 32 and the chain stop 33. Beyond the opening 31 the lever has an extension 34 in which is a hemispherical socket 35 having a slot 36 therein. Within the socket 35 is a ball 37. A hook 38 has 50 a shank 39 which is threaded into the ball, the threading of the shank 39 into the ball enabling the device to be easily assembled. Cooperating with the extension 34 for retaining the ball 37 in place is a cap member 40 secured in place by bolts 55 41. The device is used the same as the device described in connection with Figures 1 to 5. The hook 38 can rotate about the axis of the shank 39, the ball 37 turning in the socket provided for it. Lever 30 can also rock or move in a direction 60 transverse to the axis of the socket 35 through a limited arc the length of which is determined by the slot 36. The ends of the slot 36 form stops to limit the relative swinging movement of the lever similar to the abutment 12 cooperating 65 with lugs 7a and 7b.

One of the parts of the device which wears most quickly is the chain stop 22 of Figure 5 or 70 33 of Figure 8. By making the chain stop square it not only has the desired angular surfaces for cooperating with the chain, but when one edge of it wears too much, the member can be removed and turned a one quarter turn and replaced to present a new surface for engagement with the chain. The chain engaging dog can be readily 75 removed from the device for repair or replace-

ment. The spring 21 is in a protected position.

The device which is illustrated in the drawing is of rugged construction and will readily withstand the abusive use to which articles of this kind are necessarily subjected. The lever member 2 is preferably constructed of malleable iron and little machine work is required on it. Because of the universal connection between the hook and the lever the device can be used in a variety of positions and with all types of box car 10 doors. The device can also be used for moving other objects as for instance, in the sliding of heavy crates or boxes over a warehouse or loading platform. One man is enabled to open practically any box car door through the use of this 15 device in a short time.

While I have specifically illustrated and described certain preferred embodiments of my invention, it will be understood that the invention is not confined to the particular construction and 20 arrangement of the parts illustrated, but may be otherwise constructed.

I claim:

1. A car door operating tool comprising a handle member and an attaching hook universally connected to the handle, the handle having an opening therethrough, a chain engaging pawl pivotally carried by the handle in the opening and a chain stop extending across the opening adjacent the end of the pawl, the opening being closed on all sides to prevent lateral displacement of the chain.

2. A car door manipulating tool comprising a handle member having an opening therein through which an operating chain may pass, a 35 pivoted spring biased pawl in the opening for engaging a chain passing through the opening, the pawl being pivoted to ride over the links of the chain upon relative movement between the chain and handle in one direction, the pawl being restrained against movement when the handle is moved in the other direction with respect to the chain, and rigid means for pivotally attaching the handle to a car door, said opening in the handle member being closed on all sides to prevent lateral displacement of the chain.

3. A car door operating tool comprising a handle member, an attaching hook pivotally connected to the handle member, the handle member having an opening therethrough which is enclosed on all sides, a link chain passing through the opening, and a spring biased pawl pivotally carried on the handle cooperating with the chain to permit relative movement between the handle and the chain in one direction but to restrain 55 relative movement between the handle and the chain upon movement of the handle in the opposite direction.

4. A car door operating tool comprising a handle member, an attaching hook pivotally connected to the handle member, the handle member having an opening therethrough which is enclosed on all sides, a link chain passing through the opening, a pawl pivotally carried on the handle cooperating with the chain to permit 65 relative movement between the handle and the chain in one direction but to restrain relative movement between the handle and the chain upon movement of the handle in the opposite direction, and means for limiting the relative 70 movement of the handle with respect to the hook to an arc of less than 180°.

5. A car door operating implement comprising a handle member constituting a lever, a hooked member universally supported on the handle 75

- member whereby the handle member may be rocked back and forth in one direction with respect to the hook and may also be swung in a plane transverse to the plane of the first direction of movement, the handle member having an opening therethrough in that end thereof adjacent the hook, said opening being enclosed on all sides, a chain passing through the opening, a pawl carried on the handle member cooperating with the chain arranged to ride over the chain when the handle member is moved in one direction in one plane, but which locks against the chain when the handle is moved in the other direction in the same plane.
15. A car door operating implement comprising a handle member constituting a lever, a hooked member universally supported on the handle member whereby the handle member may be rocked back and forth in one direction with respect to the hook and may also be swung in a plane transverse to the plane of the first direction of movement, the handle member having an opening therethrough in that end thereof adjacent the hook, said opening being enclosed on all sides, a chain passing through the opening, a pawl carried on the handle member cooperating with the chain arranged to ride over the chain when the handle member is moved in one direction in one plane, but which locks against the chain when the handle is moved in the other direction in the same plane, and cooperating means on the hook and handle for limiting the range of back and forth movement of the handle in said plane to an arc of less than 180°.
20. A car door operating device or like implement comprising a handle member having a bifurcated end portion, a removable pin passing through said bifurcated end portion, a hook carrying member pivotally mounted on said handle member, a hook pivotally supported in said hook carrying member with its axis of rotation transverse to the axis of said pin, said handle member having an opening therethrough adjacent the bifurcated end and a cooperating fixed chain stop and movable pawl in the opening, and a link chain passing between the chain stop and the pawl, the opening being enclosed on all sides to prevent lateral displacement of the chain.
25. An implement of the class described comprising a handle member having an opening therethrough, a link chain passing through the opening, a pawl pivotally supported in the open-

ing for cooperation with the chain, means for limiting the pivotal movement of the pawl, a chain stop cooperating with the chain and pawl, said chain stop comprising a removable member extending transversely across the opening and being of non-circular symmetrical cross section whereby it may be removed and turned and replaced to present other surfaces thereof to the chain.

9. A car door operating device comprising a rigid handle member having a bifurcated end portion, a perforated web connecting the two sides of said bifurcated end, a pin passing through said bifurcated end of the handle member, an extension secured to the bifurcated end of the handle member having an eye through which said transverse pin passes and having projections extending into the perforations of said web, said extension having a laterally offset bend therein, the handle having an opening therethrough, a chain passing through the opening, and a pawl and chain stop cooperating with the chain, said extension being removable from the handle by removal of said transverse pin.

10. A car door operating implement comprising a rigid lever having a terminal portion universally pivoted thereto adapted to be engaged with a part of a car and having an opening therethrough intermediate its ends which opening is enclosed on all sides, a chain passing through the opening in the lever for engagement with another part of the car, and a pawl on the lever pivotally supported for operation in the opening for engaging the chain to permit relative movement between the chain and lever in one direction but to restrain such movement in the opposite direction and a chain stop extending across the opening and cooperating with the pawl.

11. A car door operating device comprising in combination, a chain having a hook for attachment to a car frame, a lever having a hook universally secured to one end thereof for attachment to a car door handle, said lever having an opening therein between its ends which is enclosed on all sides through which the chain passes, and a self-actuating pawl in said opening which rides over the links of the chain when the lever is moved in one direction and which locks against the links to exert a pull on the chain when the lever is moved in the opposite direction, said lever having a fixed chain stop which cooperates with the pawl.

THOMAS H. EDELBLOUTE.
